UNITED STATES PATENT OFFICE.

EDWARD A. BERG, OF BRIDGEPORT, CONNECTICUT.

METHOD OF MAKING SHEARS.

1,111,245.

Specification of Letters Patent. Patented Sept. 22, 1914.

Application filed June 18, 1914. Serial No. 845,817.

To all whom it may concern:

Be it known that I, EDWARD A. BERG, a citizen of the United States, residing at the city of Bridgeport, county of Fairfield, State of Connecticut, have invented certain new and useful Improvements in Methods of Making Shears; and I do declare the following to be a full, clear, and exact description of the invention, such as will enable others skilled in the art to which it appertains to make and use the same.

This invention relates to certain new and useful improvements in methods of making shears, and the primary object thereof is to provide a method in which the handles for the thumb and hand are both made or formed separately of the blades and are subsequently welded thereto, as distinguished from shears the two members of which are formed in a single integral piece, and are drop forged.

A further object of the invention is to provide a method of making shears in which the handles for the thumb and hand may be made of wire, or short pieces of rods or similar bar stock, or same may be made from seamless tubing, or by drawing sheet metal into cup form and then shaping and utilizing the ring formed by the flange of the cup 30 as the handles.

Other and further objects will appear later, and manifest themselves in the course of the following description.

In the drawings Figure 1 is a plan view of 35 a piece of sheet metal showing the manner in which the blade blanks are cut therefrom; Fig. 2 is a plan view of one of the cut blade blanks; Fig. 3 is a section on the line 3—3 of Fig. 2; Fig. 4 is a plan view of the blade 40 blank after the tang thereof has been formed by doubling the shank of the blank; Fig. 5 is a view similar to Fig. 4 showing in dotted lines the removal of the stock from the back of the blade; Fig. 6 is a section on the line 45 6—6 of Fig. 5; Fig. 7 is a view similar to Fig. 5, showing the blade in its final completed form; Fig. 8 is a section on the line 8—8 of Fig. 5; Fig. 9 is a plan view of the completed shears; Fig. 10 is a detail view 50 in longitudinal section taken through the pivoting screw of the shears; Fig. 11 is a plan view of a blank of wire, or rod, or the like from which the handles are formed; Fig. 12 is a cross section of Fig. 11; Fig. 13, 55 is a side elevation of the blank of Fig. 11, showing same in the first stage of its forma-

tion to provide the finished hand handle; Fig. 14 is a side elevation of the hand handle in the second stage of its formation; Fig. 15 is a side elevation of the hand handle in its final or completed form; Fig. 16 is a section on the line 16—16 of Fig. 15; Fig. 17 is a side elevation of a blank in the process of formation of one of the thumb handles; Fig. 18 is a side elevation of the thumb handle in the third stage of its formation; Fig. 19 is a side elevation of the completed thumb handle; and Fig. 20 is a section on the line 20—20 of Fig. 19.

The first step of the method is that of cutting blade blanks 1, from a section of sheet metal 2, after which the stock of the blank is cut away at 3 and 4, at the back of the blade blank, as depicted in dotted lines in Fig. 2 of the drawings, and as shown in full lines in Fig. 3.

The next step in the method consists in doubling the tang 5 to the form shown in Figs. 4 and 6, whereupon the blank appears as shown in Fig. 4, and is then cut away as 80 shown in dotted lines at 6, in Fig. 5, and as shown in full lines in Fig. 8, following which the tang at its heel end is concaved at 9, and beveled at its opposite end at 10.

The thumb and hand handles are both 85 formed substantially in the same manner, the only difference being that the size and final shape of the handles differ, the hand handles 12 being larger than the thumb handle 12^a and being of a more elliptical 90 shape than the thumb handles, which latter are possessed of more of a circular form.

The handles are formed of a length of stock 10, the ends of which are beveled at 11, the stock being formed of wire, rods 95 or bars, of suitable material, and being then curved at its ends as shown in Fig. 13, following which the blank is further bent into the form shown in Fig. 14, whereupon the hand blank is shaped as shown in Fig. 15, 100 and laterally flared, as more particularly shown in Fig. 16, while the thumb handle is given the shape shown in Figs. 19 and 20.

The final step of the method is to weld the handles to the concaved portions 9 of the 105 heels of the tangs, which weld is preferably formed at the points where the ends of the blanks, of which said handles are formed, abut, whereby the points of abutment of the ends of the blank are included in the weld. 110

The handles may be made of seamless tubing by cutting sections of proper width

therefrom and then shaping the cut sections, as is obvious, or the handles may be made by drawing sheet metal of proper gage into cup form, and then in removing the bottoms 5 of the cups to leave the rims or flanges thereof, which latter are then shaped to provide handles of proper shape.

As shown in Fig. 10, of the drawings, the pivoting screw S for the blades preferably 10 has a hemispherical part F which acts to form a ball bearing face, so to speak, that enables the blades to more easily move to and from cutting position.

What is claimed is:

- 15 1. The herein described method of making shears which consists in first cutting the blades from sheet metal stock, doubling the tangs of the blades and concaving the heel ends of the tangs, then in forming handles 20 for the thumb and hand, and finally in welding the handles to the concave heel ends of the tang.

2. The herein described method of making shears which consists in first cutting the blades from sheet metal and then in reinforcing the tangs thereof and providing same with concave heel faces, then in forming the handles for the thumb and hand, and finally in welding the handles to the concave heel faces.

3. The herein described method of making shears, which consists in first cutting the blades from sheet metal stock, then thickening the tangs of the blades, then in forming the handles for the thumb and hand, and finally in welding the handles to the heel ends of the thickened tangs.

In testimony whereof I affix my signature in presence of two witnesses.

EDWARD A. BERG.
